Atty.

INVENTOR.

UNITED STATES PATENT OFFICE.

FREDERICK A. BALLOU, OF PROVIDENCE, RHODE ISLAND.

BUTTON OR STUD FOR SHIRT-BOSOMS.

SPECIFICATION forming part of Letters Patent No. 599,489, dated February 22, 1898.

Application filed July 3, 1897. Serial No. 643,405. (No model.)

To all whom it may concern:

Be it known that I, FREDERICK A. BALLOU, of the city and county of Providence, in the State of Rhode Island, have invented a certain 5 new and useful Improvement in Buttons or Studs for Shirt-Bosoms; and I declare the following to be a specification thereof, reference being had to the accompanying drawings.

Like letters indicate like parts.

10 Figure 1 is a side elevation of my invention. Fig. 2 is a rear elevation of the same. Fig. 3 shows my improved button or bosom-stud in side elevation and illustrates the manner of inserting it in and through the eyelet-holes 15 of a shirt-bosom. Fig. 4 shows said button or stud in wearing position in the shirt-bosom and illustrates the action of the spring-tongue to keep the head or ornamental front of the button or stud in contact with the shirt-bosom.

20 My invention relates to buttons or studs for shirt bosoms or cuffs; and it consists of the combination of a disk or ornamental front with a rigid post fastened to the center thereof on the rear side and bent and curved, as 25 hereinafter described, with its free end returned in a direction parallel with said disk or ornamental front and extending nearly to the fixed end of said post, thus constituting a spring-tongue.

30 In the drawings, A represents the disk or ornamental front or head of my improved bosom-stud. At the central part of the rear surface thereof is fastened a post B, which is bent in the form shown in Fig. 1—that is to say, the portion *a* of said post extends at a right angle from said disk A and is bent with a rounded corner *b*, the portion *c* extends in an angular direction from the portion *a*, the portion *d* extends from the bend *e* in a direction 35 parallel to the plane of the disk A, and the portion *f* is bent at *g* and extends alongside of the portion *d* and thence continuously in

a straight direction toward and nearly to the portion *a*. The free end *f* is tempered and constitutes a spring-tongue.

45 This button or stud is used by inserting the end *g* of the bent post B through the eyelet-hole or opening *h* of the shirt-bosom C, and when the bent post B is pushed through the eyelet-hole in the direction of the arrow *x*, as 50 seen in Fig. 3, the spring portion or tongue *f* of said post is forced toward the portion *c* of the post until both portions *c* and *f* have been passed through the eyelet-hole. The resiliency of the spring tongue or portion *f* then 55 automatically returns it to its normal position and thereafter, by its pressure on the rear surface of the shirt-bosom, holds the disk or ornamental head A of the stud in firm contact with the front of the shirt-bosom.

60 To detach the button or stud, it is seized by the head A and drawn out, which movement compresses the spring-tongue *f* toward the portion *c* of the post B, whereupon a continued drawing movement in an angular direction causes the free end of the tongue *f* to enter into and pass out through the eyelet-hole.

65 I claim as a novel and useful invention and desire to secure by Letters Patent—

70 The improved button or stud herein described, consisting of a disk or head having an angularly-bent post rigidly fastened thereto at one end and its opposite end bent inwardly and extending freely toward the fixed 75 end of the post in the plane of said bent post and capable of a spring action in said plane, substantially as shown and for the purpose specified.

FREDERICK A. BALLOU.
